135

1126 S. 10th Street
Cooking Stoves.

Stoves and Ranges
Cooking Stoves and Ranges.

Charles J. Wood.

Design for Fronts of Ranges.

PATENTED APR 18 1871

4835

Witnesses.

H. H. Young
H. H. Young

Inventor.
Charles J. Wood,

By his Attorney,

W. H. Kapperman

United States Patent Office.

CHARLES J. WOOD, OF BALTIMORE, MARYLAND.

Design No. 4,835, dated April 18, 1871.

DESIGN FOR A RANGE.

The Schedule referred to in these Letters Patent and making part of the same.

To all whom it may concern:

Be it known that I, CHARLES J. WOOD, of the city and county of Baltimore and State of Maryland, have invented and produced certain new and original Designs for the several constituent portions of a Range-Front, of which the following is a description, reference being had to the accompanying photographic representations thereof.

One new feature of my said invention is the design and ornamentation of the peculiar-shaped shield or escutcheon, cast in alto rilievo upon each of the oven-doors of the range, with or without polished fronts, as shown by the accompanying photographs.

Another new feature of my invention is the design and ornamentation of the panel figure on the fire-door, raised from the surface of said door, with or without polished front, as shown.

Another new feature of my invention is the design and ornamentation of the several doors of the oven, as distinguished by the upper corners thereof being cut obliquely, as shown by the accompanying photographs.

Another feature of my invention is the design for the polished handle of the ash-pit door, as shown.

Another feature of my said invention is the design for the mantel-shelf, having diamond openings therein, and cast with a recess to receive the heat-pipe, as shown.

I claim as my invention and production—

The design and ornamentation of the several constituent portions of a range-front, as described and shown by the accompanying photographs.

In testimony whereof I have hereunto signed my name.

CHAS. J. WOOD.

Witnesses:

ALVAH HUBBARD,
GEORGE W. COX.